Specification for Design.

Patented Aug. 21, 1917.

Application filed April 3, 1917. Serial No. 159,558. Term of patent 14 years.

To all whom it may concern:

Be it known that I, EDWARD KOEHLER, a citizen of the United States, residing at Bridgeport, county of Fairfield, State of Connecticut, have invented a new, original, and ornamental Design for a Pair of Shears, Scissors, or Similar Article, of which the following is a specification, reference being had to the accompanying drawing, forming part thereof.

The figure is an elevation of a pair of shears or scissors, showing my novel design.

What I claim is:—

The ornamental design for a pair of shears, scissors, or similar article, substantially as shown.

In testimony whereof I affix my signature.

EDWARD KOEHLER.
